UNITED STATES PATENT OFFICE.

ALFRED L. STREETER, OF CHICAGO, ILLINOIS.

BRAKE-SHOE.

SPECIFICATION forming part of Letters Patent No. 695,419, dated March 11, 1902.

Application filed March 15, 1901. Serial No. 51,254. (No model.)

To all whom it may concern:

Be it known that I, ALFRED L. STREETER, a citizen of the United States, and a resident of Chicago, in the county of Cook and State 5 of Illinois, have invented an Improved Brake-Shoe, of which the following is a specification.

This invention relates to brake-shoes, and relates particularly to brake-shoes of the general type comprising an insert or inserts of relatively hard or soft metal secured in the face or friction-surface thereof.

A primary object of the invention is to eliminate certain objectionable features now 15 common in shoes of this type, among which may be mentioned the following: the breaking off of the attaching-lug, which allows the entire body portion of the shoe to fall and frequently results in very serious accidents; 20 loosening and falling out of the inserts or of parts thereof or the breaking off of parts of the body portion of the shoe, which occurs quite frequently and materially impairs the efficiency of the shoe, exposing sharp edges, 25 which cut the treads of the wheels in breaking in a very objectionable manner.

A further object of the invention is to provide a shoe which will be efficient for braking purposes and which may be worn very 30 thin without resorting to the use of separate plates of steel or other strong tough metal secured to the back thereof.

The invention consists of the various other features, combinations of features, and details of construction hereinafter described 35 and claimed.

In the accompanying drawings a brake-shoe of my invention is fully illustrated.

Figure 1 is a plan view of the back of a 40 shoe embodying my invention in what I now consider its preferred form. Fig. 2 is a similar view of a modified form of brake-shoe of my invention. Figs. 3 and 4 are sectional views on the lines 3 3 and 4 4, respectively, 45 of Figs. 1 and 2; and Figs. 5 and 6 are partial sectional views on the lines 5 5 and 6 6, respectively, of Figs. 1 and 2.

Referring now to the drawings, A designates the body portion of the shoe, A' an insert secured therein, and A² A³ the attaching and guide lugs, respectively, thereof.

To effect the object of the invention as it

relates to preventing the attaching-lug from breaking off, my invention consists in securing said attaching-lug A² directly and firmly 55 to the insert A'. What I now consider the preferable form of brake-shoe to effect this object is that shown in Figs. 1, 3, and 5 of the drawings, in which said attaching-lug A² is formed integral with the insert A', said insert being preferably made of strong tough metal—as wrought-iron, malleable iron, semi-steel, or the like—which will insure a connection of requisite strength between said attaching-lug and the body of the shoe. 60

In case the insert A' is made of wrought or malleable iron or other relatively soft metal the body portion A of the shoe will be formed of hard cast-iron, the soft insert giving the desired coefficient of friction and the hard 70 body portion of the shoe giving life and durability to the shoe. In case the insert A' is made of semisteel or other relatively hard metal the body portion A of the shoe will be formed of soft cast-iron, the hard insert giving 75 the wear and the soft body portion the desired frictional engagement necessary for efficient breaking. My invention, however, contemplates forming the attaching-lug A² separate from the insert and dovetailing or 80 otherwise securing said attaching-lug to said insert, as shown in Figs. 2, 4, and 6 of the drawings. In this form of the shoe the portion a of the insert to which the attaching-lug A² is directly attached is preferably raised some 85 what above the back of the shoe—say one-eighth(1/8) of an inch—thus insuring a firm connection between said attaching-lug and insert at all stages of wear of the shoe. In this form of the shoe also the attaching-lug will be 90 formed integral with the body portion A of the shoe, and to provide a strong connection between the body portion of said shoe and said attaching-lug the insert A' is cut away, as shown at a', Fig. 2, thus increasing the 95 thickness of the body portion of the shoe beneath the attaching-lug. In this form of the shoe the insert A' may be made of any desired hard or soft metal, the body portion of the shoe being relatively soft or hard, respectively, as compared therewith.

To effect the object of my invention as it relates to providing a shoe of requisite strength as the shoe approaches the limit of its wear,

a shoe of my invention comprises an insert or inserts which are of substantially the same length as the brake-shoe and which extend substantially entirely through the shoe from front to back thereof, as clearly shown in the drawings, Figs. 1 to 6, both inclusive, and which are made of strong tough metal, as wrought-iron, malleable iron, steel, or the like. With this construction it is obvious that as the brake-shoe approaches the limit of its wear the insert will provide requisite strength to prevent the shoe from breaking.

In order to bind the inserts and the body portions of the shoes securely together to prevent the inserts from becoming loose and dropping or portions of the shoe from breaking off and falling, said inserts and the body portions of the shoes are firmly dovetailed to each other, as clearly shown at a^2 , Figs. 1 and 2 of the drawings. This can be effected in a simple and economical manner in the process of making the shoes, as follows: The inserts are first formed with suitable dovetail openings in their sides or lateral faces, which preferably extend from front to back thereof. The body portions of the shoes are then cast around said inserts, the molten metal entering and filling the dovetail openings in the sides of the inserts, thus forming the dovetails a^2 . This process could of course be reversed, the body portions being formed first and the inserts afterward cast into them.

As shown, the dovetail openings a^2 are substantially circular in cross-section, the centers thereof being located inwardly from the sides of the inserts. Said openings will thus be wider back from the sides of said inserts than they are in the sides thereof in the desired manner. Any other desired form of dovetail openings may, however, be used.

The shape of the inserts is immaterial. As best adapted to effect the various objects of my present invention, however, and to combine in a single shoe the various advantages arising therefrom, I consider the form of the insert shown in the drawings to be preferable. Said insert consists of a single integral piece of suitable metal of substantially the same general outline as the body portion of the shoe, but enough smaller to give a desired body of metal outside thereof.

When inserts of size and shape substantially as shown in the drawings are used, the proper relative proportions of hard and soft metal in the faces or friction-surfaces of the shoes may be obtained by making the dovetails a^2 of suitable size. In practice, however, and in order to secure a more uniform distribution of the hard and soft metal I prefer to make the dovetails a^2 relatively small and to provide holes or openings a^3 in the inserts, which preferably extend entirely through

them and are filled with the same metal as that of which the body portions of the shoes are formed. A further advantage of this construction when the attaching-lug is made separate from the insert and is dovetailed thereto, as shown in Figs. 2, 4, and 6 of the drawings, is that by disposing one of the openings a^3 beneath the attaching-lug an additional connection is provided between said attaching-lug and the insert. The relative areas of the body portions of the shoes may be further increased, if desired, by forming the guide-lugs A^3 integral with the body portions of the shoes, suitable holes or openings being formed in or adjacent to the ends of said inserts and which preferably extend from front to back thereof to form a connection of desired size and strength between said guide-lugs and the body portions of the shoes, substantially in the manner shown at a^4 in the drawings. My invention, however, contemplates forming said guide-lugs A^3 integral with the inserts, if desired. With this construction the ends of the body portions of the shoes will preferably be dovetailed to the inserts in the same manner as the sides thereof.

In order to render the shoes stronger and to prevent their breaking, particularly in handling, I prefer to form the shoes with thin layers—say one-eighth ($\frac{1}{8}$) of an inch thick—of the metal, of which the body portions of the shoes are formed, covering the backs and the initial friction-surfaces thereof, as shown in Figs. 1, 3, and 5 of the drawings.

I claim—

1. A brake-shoe comprising an insert which is of substantially the same length as the shoe and extends practically through the shoe from front to back thereof and an attaching-lug secured directly to said insert, substantially as described.

2. A brake-shoe comprising an insert of strong, tough metal which is of substantially the same length as the shoe and extends practically entirely through the shoe from front to back thereof and an attaching-lug formed integral with said insert, substantially as described.

3. A brake-shoe comprising a body portion and a rigid insert inclosed within the body portion of the shoe and which extends to within a short distance of the back and of the initial face or friction-surface of the shoe, substantially as described.

In testimony that I claim the foregoing as my invention I have hereunto set my hand this 12th day of March, 1901.

ALFRED L. STREETER.
